CLOCK HOUSING

Harry L. Laylon, Syracuse, N.Y., assignor to Sunbeam Corporation, Chicago, Ill., a corporation of Illinois

Filed July 28, 1965, Ser. No. 86,340

Term of patent 14 years

(Cl. D42—7)

FIG. 1 is a front elevational view of a clock housing showing my new design;

FIG. 2 is a side elevational view thereof;

FIG. 3 is a top plan view thereof;

FIG. 4 is a bottom plan view thereof;

FIG. 5 is a sectional view thereof taken along the section line 5-5 of FIG. 1; and

FIG. 6 is a sectional view thereof taken along the section line 6-6 of FIG. 1.

The dominant features of the design are shown in solid lines.

I claim:

The ornamental design for a clock housing, as shown and described.
